SEPARABLE PICTURE OR MONOGRAM
FRAME FOR GIFT PACKAGES

John Byck, New York, N. Y.

Application March 30, 1949, Serial No. 1,712

Term of patent 14 years

(CL. D86—10)

To all whom it may concern:

Be it known that I, John Byck, a citizen of the United States, residing in New York city, in the county of New York and State of New York, have invented a new, original, and ornamental Design for a Separable Picture or Monogram Frame for Gift Packages, of which the following is a specification, reference being had to the accompanying drawing, forming part thereof.

Fig. 1 is a perspective view of a separable picture or monogram frame for gift packages showing my design.

Fig. 2 is a plan view thereof with the fabric member removed.

Fig. 3 is a plan view of the inner member of the separable picture or monogram frame for gift packages.

Fig. 4 is an exploded view of the separable picture or monogram frame for gift packages.

Fig. 5 is a front edge view of the inner member shown in Fig. 3, and

Fig. 6 is a side edge view thereof.

The dotted lines in Fig. 1 are for illustrative purposes only.

I claim:

The ornamental design for a separable picture or monogram frame for gift packages, substantially as shown and described.

JOHN BYCK.
